UNITED STATES PATENT OFFICE.

CHARLES J. DORRANCE, OF CHICAGO, ILLINOIS.

MOVABLE GRATE-BAR.

SPECIFICATION forming part of Letters Patent No. 451,615, dated May 5, 1891.

Application filed October 15, 1889. Serial No. 327,122. (No model.)

To all whom it may concern:

Be it known that I, CHARLES J. DORRANCE, of Chicago, in the county of Cook and State of Illinois, have invented certain new and useful Improvements in Movable Grate-Bars; and I do hereby declare that the following is a full, clear, and exact description thereof, reference being had to the accompanying drawings, and to the letters of reference marked thereon, 10 which form a part of this specification.

This invention relates to improvements in that class of grate-bars wherein the grate-surface is formed by a plurality of clips or plates removably or otherwise attached to transverse bars, which latter are movably journaled in suitable frames, whereby the grate surfaces or clips may be oscillated or rocked to and fro for the purpose of shaking the fire, breaking the clinkers, sifting the ashes, &c. 15 In this class of grates it is found that the portion of the frame or box supporting the movable transverse bars—to wit, the part or side bar provided with journal-bearings—is not covered by any portion of the fire surface or 20 clips, thus leaving a space between the end clip and the outer edge of said bar or frame varying from two to four inches. This distance is increased if the said side bar or frame is not in close proximity to the inside of the 25 fire wall or chamber. Where a single frame is employed the outer edges thereof are usually adjacent to the inner brick walls of the combustion-chamber, and it has been found in practice that the clinkers attach themselves readily to the inner surface of said 30 walls and gradually build out over the grate. This tendency is assisted by the construction above set forth, for the reason that adjacent to the inner wall of the fire-chamber is the 35 space above mentioned of from two to four inches and sometimes greater, which space is not provided with any moving or rocking part or clip. The upper edge of the side bars of the frame forms a shelf and readily catches 40 particles of live coal falling from the fire-surface, and thus assists the formation of clinkers. This evil may be somewhat remedied by the use of long rods and pokers inserted from the feed-door of the furnace. The use of such 45 implements, however, is admitted to be injurious, as the feed-door must necessarily be

left open during the operation of breaking up and removing the clinkers, thus admitting a volume of cold air, which tends to deaden the fire and also to chill the boilers and otherwise injure the same. Again, where a fire-chamber is of such width as to make it impracticable to employ rocking or shaking grates mounted upon a single frame, it is the custom to use two or more of such sets of 50 grates, and when so employed the frames supporting the different sets of grates are placed side by side. It will be obvious that in such case the space between the proximate edges of the adjacent end clips is doubled by the 55 juxtaposition of the frames, making a dead space, so to speak, of from four to eight inches or more in the center of the fire-chamber and also leaving a dead space of from two to four inches at each side of the fire-chamber, as 60 above mentioned, when but a single frame is employed. It is very important that a live fire-surface extend from wall to wall within the fire-chamber. An attempt has therefore been made to overcome the disadvantages attendant on the presence of this dead space in 65 the center of the fire-chamber (where the fire is usually the hottest and where it is necessary to agitate the burning coals in order to prevent the formation of clinkers) by covering the same with long stationary grate-bars running parallel with the supporting-frames. The use of these bars also requires the use 70 of stoking implements, as above explained, and is attended with the same objectionable 75 features. It is found in practice that where movable and stationary metal parts compose the fire-surface the stationary plates burn out first and have to be frequently renewed. 80

To remedy the above evil is the object of 90 the present invention; and the same consists, primarily, of covering said dead spaces with movable fire-surface, as hereinafter set forth. By forming a movable grate-surface extending entirely across the width of the 95 fire-chamber a live even fire may be maintained at all points on the grate.

The invention will be more fully understood by reference to the following description and the appended claims.

Figure 1 is a perspective view of a grate-bar embracing my invention. Fig. 2 is a

transverse vertical sectional view of the adjacent ends of two grate-bars when used in a single combustion-chamber. Fig. 3 is an enlarged side elevation of a portion of the sup-

- 5 porting-frame and grate-bars carried thereon. Fig. 4 is a partial plan view of the same. Fig. 5 is a partial vertical sectional view taken upon line 5 5, Fig. 3, and looking in the direction indicated by the arrows. Fig. 6 is a 10 perspective view of one of the end clips.

In said drawings, A represents the fire-front, having feed-doors *a* and ash-doors *a'*.

- B is the frame connected with the fire-front A by a dead-plate A'. The frame B consists, 15 essentially, of side bars B', having depending legs or supports *b* at each end, which pieces B' are connected at their end by the usual transverse end bars B². I sometimes dispense with the end bars B². In such cases the side 20 bars B' may be secured directly to the inside of the side walls B³ of the combustion-chamber and the legs *b* dispensed with. At suitable intervals along the upper surface of said bar B' are the journal-bearings *b'*.

- 25 C are transverse bars provided at either end with trunnions *c*, adapted to fit and rotate in the journal-bearings *b'*. In the drawings I have shown said trunnions *c* as located upon one side of a line drawn vertically 30 through the center of the bar C; but my invention is not to be limited to such construction, it being obvious that said trunnions *c* may be located centrally of the bars C, if desired. I have also shown all said trunnions *c* 35 as being journaled in the same horizontal plane, and while such construction is preferred it is not insisted upon, as it will be manifest that said journal-bearings may be located in different horizontal planes.

- 40 Depending from the transverse bars C, and preferably depending from the center of said bars, are the arms C'.

D D' are suitable bars or links, each connected with one-half of the whole number of 45 bars C'. The link D is secured to each alternate arm C', while the link D' is secured to the remaining arms C'.

D² is an arm or lever pivoted at *d* to the inside of the plate A.

- 50 D³ D² are connecting-links joining, respectively, the upper and lower ends of the arm D² with the links D D'.

- A lever E is pivoted to the outside of the frame A at *e*. The upper end of said lever E 55 is adapted to receive a handle E', by which the same may be operated. The lower end of said lever E is connected by a link E² to the lower end of the lever D². The link E² passes through a suitable slot or opening *a'* 60 in the frame A. It will be manifest from the construction thus described that by rocking the handle E' to and fro an oscillating or rocking motion will not only be imparted to the transverse bars C and to the grate-surface 65 carried thereon, but that said bars will be moved in opposite directions by reason of the attachment of the bars to the alternate de-

pending arms C', as more clearly shown in Letters Patent No. 403,255, issued to me May 14, 1889.

70 F F are metallic clips, each consisting of a plate having a curved fire surface or edge *f*, and two depending members or prongs *f'*. Preferably said clips are loosely and removably placed upon the transverse bars C at 75 suitable intervals, but they may be cast integral with said bars or may be otherwise secured thereto. Each of the bars C may be provided with proper notches or cut-away portions *c'* at proper intervals for the reception 80 of the members *f'* of the clips F when said clips are separately cast. The end clips F' are each provided with one or more sections or ribs cast integral therewith, such construction being more definitely illustrated in Fig. 85 6, wherein two such sections are shown. The section or part F² is precisely similar in shape to the clip F', but is minus the depending members *f'*. It is connected to the clip F' by the web *f'*. The extension F³ has the same 90 fire-surface as the other two members, and is attached to the section F² by the web *f''*. The member F³ is provided, however, with a strengthening-rib *f'*, convex in contour, which usually will extend down to within proper 95 clearing distance of the upper part of the trunnions *c*.

The upper portion or edge of the side frame B' is cut away or hollowed out between the journal-bearings *b'*, as clearly shown in Fig. 3. The hollowed-out portions are chamfered away, as shown at *b*² *b*³, so that any ashes or bits of coal falling thereon will not be caught thereby, but will slide below to the ash-pit. The cutting away of the side bar, as shown, 105 is a great advantage, in that it affords a free air-passage below the end clips.

110 It will be obvious from the construction shown and described that the clips F' and their extensions F² F³ cover the dead spaces above referred to by extending out over the trunnions *c*, the journal-bearings *b'*, and the upper edge of the side bars B'. It will also be obvious that by the oscillation of the grate-bars C the end clips F² and F³ will have a 115 shearing action underneath and against any clinkers which might temporarily form on the side wall when the grate-bars are stationary. The cut-away portions of the upper part of the frame B' permit the necessary oscillating 120 movement of the extensions F² F³ of the end clips F'.

125 Where more than one set of bars are used in a combustion-chamber, the adjacent end clips F' of each set make a continuous movable fire-surface at the center of the fire-chamber, and I am thus enabled to dispense with the stationary grate-bars above mentioned.

130 In my said Letters Patent I have shown a rocker-shaft at the rear of the transverse grate-bars, to which shaft the arms depending from the several grate-bars are connected. Such construction is not always convenient where there is a very small space be-

low the grate-bars—as, for example, in locomotive ash-pans. I have, therefore, devised the present form of leverage, whereby a comparatively low ash-pit may be utilized.

5 When more than one frame is employed in a single fire-chamber, as shown in Fig. 2, a single side bar B' may be employed of sufficient width to carry the adjacent trunnions c .

It will be understood, of course, that the 10 same advantages will be attained if the sections F^2 and F^3 are united and cast solidly to the clip F' , forming an inverted-L-shaped (Γ) end clip. It will also be understood that I may use more than one connecting rib or web f^2 15 f^3 to connect, respectively, the several parts of the end clip.

It may be mentioned that the dead space on the sides of the grate in locomotive fire-boxes is particularly injurious thereto, the 20 side sheets of the fire-box corroding by the accumulation of clinkers and other refuse, thus requiring frequent renewals of the same. With my invention, as above set forth, this objection is entirely overcome.

25 It will be noticed that the trunnions c are integral with the grate-bar C , and that they are shown as located at the ends of said bar; but it will be understood, of course, that where the grate-bar C is of great length, owing to 30 an unusually wide fire-chamber in which it is to be used, an intermediate support or trunnion may be formed without departing from the essential features of my invention. This is obvious from an inspection of Fig. 2 of the 35 drawings, such construction requiring merely the joining of two adjacent end pinions c of the two grate-bars C . In such case the end clips F' may be placed on either side of the trunnions, as shown in said Fig. 2, or the 40 adjacent extensions F^3 of each clip may be united directly, or by a suitable web, as f^3 . I have seen fit to illustrate this modification, as will be perfectly obvious from an inspection of Fig. 2.

I claim as my invention—

45 1. In a grate, the combination of a plurality of movable grate-bars, each provided with trunnions integral therewith, and a support for the same having bearings for said trunnions, said grate-bars having removable 50 fire-surfaces extending over said trunnions and bearings, substantially as described.

2. The combination of a plurality of movable grate-bars, each provided with suitable trunnions located on one side of a line drawn 55 vertically through the center of said bars, and a support for the same provided with bearings for said trunnions, said grate-bars being provided with removable fire-surfaces extending over said trunnions and journals, 60 substantially as described.

3. The combination of a plurality of pivoted oscillating grate-bars, each provided with suitable integral trunnions, and a support for the same provided with bearings for said 65 trunnions, said support having a recessed or cut-away portion between said bearings, and said grate-bars being provided with fire-surfaces extending over the trunnions, bearings, and support, substantially as described. 70

4. The combination of a plurality of movable grate-bars having trunnions at their ends located on one side of a line drawn vertically through the center of said bars, and a support for the same provided with bearings 75 for said trunnions, said grate-bars being provided with fire-surfaces extending over the said trunnions and bearings to points flush with or outside of said bearings, substantially as described. 80

In testimony that I claim the foregoing as my invention I affix my signature in presence of two witnesses.

CHARLES J. DORRANCE.
